DOOR LATCH

Alex Sorenson, Cambridge, Minn.

Application July 11, 1947, Serial No. 760,339

2 Claims. (Cl. 292—226)

1

This invention relates to a latch structure such as used for holding a door in closed position.

It is an object of this invention to provide a novel, simple and efficient latch and one which is quite rugged and durable.

It is a further object of the invention to provide a latch structure for a door comprising a latch bar pivoted adjacent one end for oscillating movement at one side of the door, a keeper on the door frame adapted to receive the other end of said bar, means secured to the door and having handles at both sides of said door adapted to be oscillated for lifting said latch, and a spring of novel and efficient form for urging said latch downwardly.

These and other objects and advantages of the invention will be fully set forth in the following description made in connection with the accompanying drawings in which like reference characters refer to similar parts throughout the several views and in which:

Fig. 1 is a view in side elevation of the structure as seen from one side of the door, which side is preferably the outer side;

Fig. 2 is a horizontal section taken substantially on line 2—2 of Fig. 1, as indicated by the arrows;

Fig. 3 is a vertical section taken substantially on line 3—3 of Fig. 1, as indicated by the arrows;

Fig. 4 is a vertical section taken on line 4—4 of Fig. 1, as indicated by the arrows, shown on an enlarged scale; and

Fig. 5 is a vertical section taken on line 5—5 of Fig. 1, as indicated by the arrows.

Referring to the drawings a door 10 is shown which will be as usual mounted to swing on hinges at one side, said door swinging about a vertical axis. A door frame 11 is disposed adjacent the free edge of said door. A latch bar 12 is provided and while this might be variously formed, in the embodiment of the invention illustrated it is shown as a flat bar substantially rectangular in cross section. A plate 13 is provided having a portion 13a which fits against the side of door 10 and is secured thereto by a plurality of screws or bolts 14 extending through suitable holes in portion 13a. Plate 13 has a portion or flange 13b at one end which extends outwardly from the door substantially at right angles thereto. Portion 13b is provided with an elongated vertically extending opening or slot 13c. One end of bar 12 extends through said opening or slot 13c and said bar is provided with a notch 12a in its lower side having diverging sides, which notch embraces the part of portion

2

13b at the bottom of opening 13c. Bar 12 can thus oscillate vertically, the same fulcruming about the inner end of notch 12a. A spring 16 is provided and while this could take various forms, in the embodiment of the invention illustrated it is shown as a small rod or wire of resilient material. Portion 13b has a hole or slot 13d at its upper end and one end of spring 16 extends through said opening 13d and has its end 10 bent downwardly at the inner side of portion 13b. Spring 16 extends downwardly in curved form about the end of latch 12 and then extends through another slot or opening 13e in the bottom of portion 13b. Spring 16 then extends 15 longitudinally of bar 12 toward the free end thereof and then extends upwardly substantially vertically along one side of bar 12 and has its end portion extending over said bar and down along the side thereof adjacent door 10. It will thus 20 be seen that the tension of spring 16 urges bar 12 downwardly. A keeper 17 is provided which will be secured to door frame 11 in any suitable manner, as by a plurality of screws 18. Keeper 17 has an inner substantially vertical side 17a spaced from door frame 11 to form a slot or recess adapted to receive the free end of bar 12. The top and outer sides of keeper 17 are of curved form so that the outer side thereof acts as a cam to raise the free end of bar 12 when the latter 25 engages said keeper. A member 20 in the form of a plate is secured to the side of the door opposite plate 13 in any suitable manner as by a plurality of screws 21. Plate 20 at its lower end is bifurcated and the two spaced portions thereof 30 are formed into substantially cylindrical form. A member 22 is provided, and while this could be variously made, in the embodiment of the invention illustrated it is shown as made from a cylindrical rod, the same having trunnions 22a secured thereto at opposite sides which extend into and are oscillatable in the semi-cylindrical portions 20a of plate 20. Member 22 extends through an opening or slot 10a formed in the door 10. The opening in plate 20 extends to the 35 top of this slot. A plate 24 is secured to the side of the door at which latch 12 is disposed, in any suitable manner, as by a plurality of screws 25. While plate 24 could take various forms, it is shown as oblong. Plate 24 has a slot 24a therein 40 which is coextensive with the slot 10a. The member 22 extends under the latch bar 12 and has downwardly extending and diverging portions 22b forming handles. A guide bracket 26 formed of a strip of metal is secured to the side 45 of door 10 by suitable screws 27. Plate 26 has a

portion 26a offset from door 10 forming an opening in which latch bar 12 is guided.

In operation, when the door is to be held in closed position, latch bar 12 will be in the position shown in Figs. 1 and 5. The free end of bar 12 is then disposed in the keeper 17 and between the same and the door casing or wall 11. When the door is to be opened the operator can take hold of either one of the handles 22b depending on which side of the door he is located. If he is on the side of the door at which bar 12 is disposed, he will lift handle 22b and member 22 will pivot about trunnions 22a so that latch bar 12 will be lifted above keeper 17. The door can then be opened. If the operator is at the opposite side of the door he will press downwardly on the handle 22b and this will swing member 22 and lift the latch bar 12. If the door is open and swings to closed position, the latch 12 will be guided upwardly by keeper 17 and when it passes the top of the keeper it will be thrown into the space between the surface 17a and the door frame by spring 16. Spring 16 exerts a tension on bar 12 tending to move its free end downwardly and this tension holds the latch bar in closed position.

From the above description it will be seen that I have provided a simple, efficient and very rugged structure of door latch. The parts are easily made from standard material. The spring 16 can be very readily disengaged from bar 12 as well as from plate 13 and bar 12 can be readily removed from plate 13. The latch can be operated from either side of the door and it securely holds the door in closed position. The device has been amply demonstrated in actual practice, found to be very successful and efficient and commercial production of the same has been started.

It will of course be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:

1. A latch structure for a door having in combination, a plate having a portion adapted to be secured to the side of said door, said plate having a second portion extending outwardly of said door, said second portion having a vertical slot therein and being provided with a pair of notches respectively at its top and bot-

tom, a latch bar having one end extending through said slot and having a notch at its lower side embracing said second portion at the bottom of said slot, said bar thus being movable vertically in said second portion, said bar being adapted to cooperate with a stationary keeper, means mounted on said door and having handles at both sides of said door for lifting said latch, and a spring comprising a resilient small rod or wire having one end bent inwardly and disposed in said notch in the upper end of said second portion, said spring extending downwardly to be disposed in said lower notch and about the lower end of said second portion, said spring thence extending outwardly of said second portion and longitudinally of said latch bar and having its free end portion extending upwardly and over the top of said latch bar being disposed thereon, and said spring acting to urge said bar downwardly.

2. A latch structure for a door having in combination, a bracket secured to a door having a plate-like portion extending outwardly from said door and having a slot therein, said portion having a pair of notches respectively in its top and bottom ends, latch bar having one end disposed in said slot and having a notch in the lower side of said end embracing the bottom of said slot, a means for raising said latch bar, a wire spring, said spring having one end bent to engage and be removably held in said notch at the top of said plate-like portion, said spring disposed downwardly to engage said notch in the lower end of said plate-like portion and said spring thence extending outwardly at an angle to said plate-like portion and longitudinally of said latch bar, the free end of said spring extending upwardly and over said latch bar being disposed thereon for urging the same downwardly.
